UNITED STATES PATENT OFFICE.

TIBERIUS C. COLTON, OF GRISWOLD, MANITOBA, CANADA.

WASHBASIN.

No. 892,366.

Specification of Letters Patent.

Patented June 30, 1908.

Application filed July 31, 1907. Serial No. 386,462.

To all whom it may concern:

Be it known that I, TIBERIUS C. COLTON, a subject of the King of Great Britain, residing at Griswold, in the Province of Manitoba and 5 Dominion of Canada, have invented certain new and useful Improvements in Washbasins, of which the following is a specification.

This invention relates to wash basins or lavatories, and it has for its object to provide 10 an improved closure for the waste pipe with which this class of devices are usually provided.

It is customary to attach the plug or closure by means of a chain to the basin or to 15 the stand supporting the basin in such a manner that the plug may be readily inserted into the waste pipe; this is objectional for various reasons; the chain is easily broken and the plug lost or displaced; the chain is 20 apt to become coated with lather, causing dirt to adhere, and inducing an unsanitary condition; and in using the basin the plug is apt to become displaced from the pipe, by the hands being tangled with the chain, thus 25 causing the water to escape, and necessitating a fresh supply. These various objections are overcome by the present invention which consists in the improved construction and novel arrangement and combination of 30 parts which will be hereinafter fully described and particularly pointed out in the claims.

In the accompanying drawing has been 35 illustrated a simple and preferred form of the invention; it being, however, understood that no limitation is necessarily made to the precise structural details therein exhibited, but that changes, alterations and modifications within the scope of the invention may 40 be resorted to when desired.

In the drawing, Figure 1 is a top plan view of a wash basin equipped with the invention. Fig. 2 is a vertical sectional view of the same.

Corresponding parts in both figures are 45 noted by like characters of reference.

The basin 1 is of ordinary construction consisting of a bowl which is set and supported in a stand including a top piece or slab 2. The bowl or basin 1 is provided with 50 the overflow duct 3 and with the waste aperture 4 with which is suitably coupled or connected the waste pipe 5.

6 is a lever, curved to correspond with the interior contour of the bowl or basin, and 55 having connected therewith a plug 7 adapted

to form a closure for the waste aperture 4. The lever 6 extends to the upper edge of the front portion of the bowl, and is terminally curved or bent to form a finger piece 8. The lever 6 is hingedly connected with a plate or 60 supporting member 9 which is also curved to correspond with the interior contour of the bowl upon which it is secured, near the upper edge of the rear portion of said bowl, by means of bolts or rivets 10.

It will be seen that the top piece or slab 2 with which the bowl is connected extends slightly beyond the rim or upper edge of the bowl, so as to form an inward extending flange 11; the bent portion or finger piece 8 of the lever 6 will readily enter into locking engagement with said flange, thus securing said lever in position with the plug 7 engaging the aperture 4, the inherent resiliency of the lever tending to hold it in locking engagement with the flange 11. By pressure upon the free end of the lever it may be readily disengaged and raised to the position shown in dotted lines in Fig. 2, thus disengaging the plug 7 from the aperture 4 and 80 permitting the water contained in the bowl or basin to escape.

The plate or supporting member 9 may be advantageously utilized for clamping or securing in position upon the rear wall of the 85 wash bowl a soap cup or receptacle 12 which has been shown as provided with apertures or drip openings 13 and with a downward extending flange 14 inserted and clamped between the plate 9 and the adjacent face of 90 the wash bowl. In this manner, a soap cup or receptacle may be conveniently secured in a position where all drippings are discharged directly into the wash bowl or basin, and whereby cleanliness and sanitation are obvi- 95ously promoted.

Having thus fully described the invention, what is claimed as new is:—

A wash bowl having a waste aperture, a supporting member secured in the bowl, a 100 soap cup having a flange clamped between the supporting member and the bowl, a lever pivoted upon the supporting member, and an aperture engaging plug mounted upon the lever.

TIBERIUS C. COLTON.
